MULTIPLE ELECTRIC PLUG RECEPTACLE

Daniel Lancelot, Pittsburgh, Pa.

Application October 7, 1950, Serial No. 189,005

4 Claims. (Cl. 339—76)

1

This invention relates generally to electrical plug receptacles and more in particular to a plug receptacle which may be plugged into a standard flush mounted plug receptacle forming a permanent part of the wiring of a building.

Numerous variations of plug-in types of plug receptacles are available for multiplying plug-in facilities at a particular plug receptacle. In most of these, the plug-in receptacle comprises a housing of electrical insulating material having plug receptacles, in several of the faces thereof, connected to a pair of protruding prongs adapted to plug into a standard flush mounted receptacle. Usually three, and sometimes more, plug receptacles are provided in the faces of the plug-in unit. Thus the facilities of a single outlet, by such an expedient, are increased at least three fold. Thus a concentration, for example, of household electrical devices such as appliances and portable lighting units may be conveniently handled.

The mechanics of such an arrangement however, are poor. The entire mechanical load hangs on the prongs of the plug-in plug receptacle and after a short period of time, mechanical failure of the flush mounted plug receptacle occurs. Since this last-named receptacle is essentially a permanent part of the wiring system, its replacement is a matter of some consequence. Plug-in receptacles of this type, therefore, do not represent an adequate solution to the problem.

One object of this invention is to provide a plug-in type of plug receptacle which may be securely mechanically attached to a standard flush mounted plug receptacle forming a permanent part of a wiring system.

More in particular it is an object of this invention to provide a plug-in type of plug receptacle having two pairs of plug connectors for plug-in connection with a standard double plug receptacle of the flush mounted type wherein provision is had for securely mechanically attaching the plug-in plug receptacle to the standard plug receptacle.

It is also an object of this invention to provide plug-in plug receptacles of the character referred to in the preceding objects with a plurality of plug receptacles therein.

The foregoing statements are merely illustrative of the various aims and objects of this invention. Other objects and advantages will become apparent upon a study of the following disclosure when considered in conjunction with the accompanying drawing, in which:

Fig. 1 is a plan view of a plug-in type of plug

2

receptacle embodying the principles of this invention;

Fig. 2 is a longitudinal sectional view of the plug-in plug receptacle of Fig. 1;

Fig. 3 is a bottom plan view of the plug-in plug receptacle of Fig. 1; and

Figs. 4, 5 and 6 are, respectively, sectional views taken on the lines IV—IV, V—V and VI—VI, respectively, of Fig. 2.

10 The several illustrations of the drawing illustrate a preferred embodiment of this invention designed for plug-in connection to a standard double flush mounted plug receptacle of the type permanently wired into a wiring system. These 15 standard plug receptacles are usually placed in a wall of a building, in keeping with the electrical code, and are mounted in metal boxes, secured to the building frame in such a position that the edges defining the open end of the box are substantially at the finished surface of the wall. Such a box is not shown in the interest of simplicity. The standard plug receptacle is fitted into the box and secured thereto by means of screws (not shown). In the case of a double 20 plug receptacle, as 1 (or duplex convenience outlet as it is sometimes known), when mounted in the box, each plug receptacle face 2 protrudes about one-eighth of an inch beyond the wall surface. A cover plate 3 of rectangular plan- 25 forming having a pair of openings therein neatly fitting about the edges of the faces of the plug receptacles covers the box opening and seats against the wall. In practice, a cover plate mounting screw clears through the cover plate and threads into a threaded hole in the plug receptacle between the plug receptacle faces to secure the cover plate in position. Alternatively 30 some standard receptacles may require the use of two screws in mounting the cover plate.

35 40 The present invention contemplates establishing electrical connections in the two plug receptacles of a standard double plug receptacle, for a plurality of plug receptacles in a single insulating block and securing the assembly in position by a screw or screws as required clearing through the plug receptacle block and threadedly engaging the threaded hole in the standard double plug receptacle.

45 In Figs. 1, 2 and 3, the insulating receptacle 50 base or housing is designated 5 and is provided with four plug receptacles 6a, 6b, 6c and 6d which are grouped in pairs on opposite sides of a longitudinal center line through the base. In Fig. 1, the position of the standard double plug receptacle is indicated by the individual plug recep-

tacle 2, in dotted outline, and the position of the standard receptacle cover plate 3 is also indicated in dotted outline. As will be seen from the bottom view of Fig. 3, the plug-in type of plug receptacle of this invention is provided with two pairs of plug prongs 1a, 1b and 8a, 8b, respectively, which are suitably spaced along the base in correspondence with the spacing of the prong receiving openings 9 of the standard double plug receptacle 1.

The prongs 1a, 1b, 8a and 8b may be an integral part of, or otherwise suitably joined to, a plurality of current carrying strips secured in suitable cavities in the insulating base 5 to provide circuit connections to the respective plug receptacles 6a through 6d. To this end, prong 1a is integrally formed with strip 1c which extends between the prong-receiving openings 10 and 11 of the plug receptacles 6c and 6d, respectively. Prong 1b is an integral part of a U-shaped metal strip 1d, being formed at the end of the short leg thereof. The bight of the U-shaped strip 1d extends around the prong 1a and the long leg of the U-shaped member straddles the prong-receiving openings 12 and 13 of plug receptacles 6c and 6d, respectively. Contact strips 1e and 1f, which may be an integral part of strips 1c and 1d, respectively, project upwardly into openings 10 and 12 adjacent one side thereof (see Fig. 5) to slidably engage the prongs of a standard plug connector to be plugged therein. Prong-receiving openings 11 and 13 have similar contact strips (not shown), integrally formed with strips 1c and 1d, fitted therein. Strips 8c and 8d, corresponding respectively to strips 1c and 1d, are integrally formed with prongs 8a and 8b and each is provided with contact strips projecting into prong-receiving openings 14, 15, 16 and 11. Contact strips 8e and 8f which are integrally formed with strips 8c and 8d are shown in Fig. 5 in their respective positions in prong-receiving openings 14 and 16 of plug receptacle 6a. This construction connects plug receptacles 6a and 6b in parallel and connects plug receptacles 6c and 6d in parallel, doubling the plug receptacle capacity of the standard double plug receptacle 1.

As earlier noted, each of the strips 1c, 1d and 8c, 8d are disposed in suitable cavities in the base or housing 5. Suitable means for securing these strips in the base is represented in the mounting tabs 18 integrally formed with the respective strips and secured to the base by screws 19 which clear therethrough and threadedly engage the base. The details of this mounting appear in Figs. 3 and 6. The bottom of this plug-in type of plug receptacle is covered with a sheet of material of electrical insulating material 20 (not shown in Fig. 3) to insulatedly enclose the metal strips 1c, 1d, 8c and 8d. Prongs 1a, 1b, 8a and 8b project through suitable openings in this sheet 20. In the illustrated embodiment a marginal skirt 21 is provided, the bottom edges of which engage the finished wall surface and space the unit a sufficient distance from the wall surface to clear the faces of plug receptacles 2 of the standard double plug receptacle. The unit is securely mounted to the standard plug receptacle 1 by a screw 22 which clears through the insulating base or housing 5 and threads into the threaded hole in standard plug receptacle 1 which normally receives the cover plate screw, affording a strong mechanical connection completely relieving the prongs in the plug receptacle 6a through 6d of mechanical load.

While two pairs of plug receptacles have been 76

illustrated, it will be appreciated that the parallel connections may be extended to include any number of plug receptacles within practical limits. Although the present design has been made to straddle the cover plate 3 for the standard receptacle 1 so that the cover plate need not be removed, it will be appreciated that other designs may be made which are exactly the size of the standard double receptacle cover plate, removal 10 of the cover plate being optional. In any event, the unit is preferably of such a size as to completely cover the standard receptacle and its mounting box as does the standard cover plate.

It will be appreciated that numerous variations 15 in design details with regard to the configuration of parts and the location of the plug receptacles of this plug-in fixture may be had without departing from the spirit and scope of this invention. Accordingly, it is intended that the foregoing disclosure and the illustrations of the drawings shall be considered only as illustrative of the principles of this invention.

I claim:

1. An electrical convenience outlet unit for attachment to a standard built-in, flush mounted, convenience outlet having two conventional plug receptacles and at least one threaded hole for receiving a cover plate mounting screw, comprising, in combination, a base of electrical insulating material, two pairs of metal bayonet prongs fitted and secured in said base in positions to plug into the two conventional plug receptacles, respectively; a metal strip connected to one prong of one of said pairs of prongs and secured in said base, a second metal strip corresponding to the first-mentioned metal strip secured to a prong of the other pair of prongs positioned diagonally opposite said first-mentioned prong, said second metal strip being secured in said base in a position substantially paralleling and opposite to said first-mentioned metal strip, metal strips connected to the remaining prong of each pair of prongs and secured in said base in parallel spaced relation with the metal strip connected to the other prong of that pair forming spaced pairs of metal strips, said base having spaced pairs of openings therethrough into said spaced pairs of metal strips for permitting the entrance of the prongs of standard electrical plugs into engagement with the respective pairs of metal strips, whereby a plurality of parallel connections is afforded with each pair of metal strips, and a mounting screw clearing through said base and adapted to engage the threaded hole in the standard convenience outlet to secure said base over the standard convenience outlet.

2. An electrical convenience outlet unit for attachment to a standard built-in, flush mounted, convenience outlet having two conventional plug receptacles and at least one threaded hole for receiving a cover plate mounting screw, comprising, in combination, a base of electrical insulating material, two pairs of metal bayonet prongs fitted and secured in said base in positions to plug into the two conventional plug receptacles, respectively; a metal strip connected to one prong of one of said pairs of prongs and secured in said base, a second metal strip corresponding to the first-mentioned metal strip secured to a prong of the other pair of prongs located in a position diagonally opposite said first-mentioned prong, said second metal strip being secured in said base in a position substantially paralleling and opposite to said first-mentioned metal strip, metal strips connected to the remaining prong

of each pair of prongs and secured in said base in parallel spaced relation with the metal strip connected to the other prong of that pair forming spaced pairs of metal strips, said base having spaced pairs of openings therethrough into said spaced pairs of metal strip for permitting the entrance of the prongs of standard electrical plugs into engagement with the respective pairs of metal strips, whereby a plurality of parallel connections is afforded with each pair of metal strips, and a mounting screw clearing through said base and adapted to engage the threaded hole in the standard convenience outlet to secure said base over said standard convenience outlet, said base including a portion having marginal edges sufficient to completely cover the standard convenience outlet.

3. An electrical convenience outlet unit for attachment to a standard built-in, flush mounted, convenience outlet having two conventional plug receptacles and at least one threaded hole for receiving a cover plate mounting screw, comprising, in combination, a base of electrical insulating material, two pairs of metal bayonet prongs fitted and secured in said base in positions to plug into the two conventional plug receptacles, respectively; a metal strip connected to one prong of one of said pairs of prongs and secured in said base, a second metal strip corresponding to the first-mentioned metal strip secured to a prong of the other pair of prongs located in a position diagonally opposite said first-mentioned prong, a first U-shaped metal strip having a long leg and a short leg, said short leg being connected adjacent its extremity to the remaining prong of said one pair of prongs and the long leg thereof being secured in said base in a position paralleling and spaced from the first-mentioned metal strip forming one pair of spaced metal strips, a second U-shaped metal strip having a long leg and a short leg, the short leg of the second U-shaped metal strip being connected to the remaining prong of the other pair of metal prongs and the long leg thereof being secured in said base in a position paralleling and spaced from said second metal strip forming a second pair of spaced metal strips, said base having spaced pairs of openings into said spaced pairs of metal strips for permitting the entrance of the prongs of standard electrical plugs into engagement with the respective pairs of spaced metal strips whereby a plurality of parallel connections are afforded with each pair of metal strips, and a mounting screw clearing through said base and adapted to engage the threaded hole in the stand-

ard convenience outlet to secure said base over the standard convenience outlet.

4. An electrical convenience outlet unit for attachment to a standard built-in, flush mounted, convenience outlet, having two conventional plug receptacles and at least one threaded hole for receiving a cover plate mounting screw, comprising, in combination, a base of electrical insulating material, two pairs of metal bayonet prongs fitted and secured in said base in positions to plug into the two conventional plug receptacles, respectively; a metal strip connected to one prong of one of said pairs of prongs and secured in said base, a second metal strip corresponding to the first-mentioned metal strip secured to a prong of the other pair of prongs located in a position diagonally opposite said first mentioned prong, a first U-shaped metal strip having a long leg and a short leg, said short leg being connected adjacent its extremity to the remaining prong of said one pair of prongs and the long leg thereof being secured in said base in a position paralleling and spaced from the first-mentioned metal strip forming one pair of spaced metal strips, a second U-shaped metal strip having a long leg and a short leg, the short leg of the second U-shaped metal strip being connected to the remaining prong of the other pair of metal prongs and the long leg thereof being secured in said base in a position paralleling and spaced from said second metal strip forming a second pair of spaced metal strips, said base having spaced pairs of openings into said spaced pairs of metal strips for permitting the entrance of the prongs of standard electrical plugs into engagement with the respective pairs of metal strips whereby a plurality of parallel connections is afforded with each pair of metal strips, and a mounting screw clearing through said base and adapted to engage the threaded hole in the standard convenience outlet to secure said base over the standard convenience outlet, said base including a portion having marginal edges sufficient to completely cover the standard convenience outlet.
